UNITED STATES PATENT OFFICE

2,502,034

SEPARABLE BUTTON

Gordon O. Bowie, Spartanburg, S. C.

Application December 6, 1946, Serial No. 714,568

1 Claim. (Cl. 24—108)

1

This invention relates to improvements in separable buttons, and has as its primary object the provision of a device permanently secured to a garment on which buttons may be placed and removed at will.

Another object of this invention is a provision of such a button holding device of the character described which is adapted to be permanently secured to a garment, and a device which may remain on the garment at all times without becoming damaged through washing, dry cleaning, or the like.

Another object of this invention resides in the provision of a device of the character described which is easily operable and adapts the buttons on a garment to be quickly and easily removed when the garment is to be cleaned or washed, and a device which enables the buttons on the garment to be replaced at will to match accessories to be worn with the garment.

Still another object of this invention is the provision of a new and novel button holding device of the character described which is of durable, simple, and inexpensive design.

Further improvements and advantages of this invention will readily appear to those skilled in the art when the following description is read in the light of the accompanying drawings in which:

Fig. 1 is a front elevation of the button holding device.

Fig. 2 is a front elevation of the garment securing means.

Fig. 3 is a back plan view of the button securing device.

Fig. 4 is a side elevation of the spring clip.

Fig. 5 is a vertical cross section taken on line 5—5 of Fig. 3.

Figure 6 is a side elevation of one member of the button holder separated from its companion member.

Figure 7 is a side elevation of the other member of the button holder separated.

Fig. 8 is a front elevational view of another form of button holding device.

Referring now to the accompanying drawings in which like numerals indicate similar parts throughout, A designates a flat, circular metallic plate which is provided with raised spikes 1 circumferentiating the plate at a spaced distance inward of its circumference, these spikes 1 being formed by punching out the plate from the rear with a triangular punch. A raised hub 2 is centered on the front of the plate A and comprises a circular boss with a hollowed cavity 3 extend-

2

ing inward from the front thereof. The plate A is positioned behind the garment 4 at a position where a button is desired and the garment is cut to receive the circular boss 2 therethrough.

5 When the boss 2 is inserted through the aperture 5 in the garment 4 the spike members 1 are forced through the garment at the apertures 6 provided therefor.

A second member B being circular in shape 10 and comprising a second plate 7 similar to plate A which has a turned-over edge 8 about its circumference which forms a hooked end thereon, the open side of said hooked end being inwardly disposed toward the garment 4. This hook 15 about the circumference of the plate 7 is adapted to receive the spikes 1 of the plate A when they are disposed through the garment 4 in such a clamp as to securely fasten the second member B to the face or front of the garment at such a 20 position where a button is desired.

The plate 7 is flanged outwardly to form a raised hub 9 which is hollowed out within to form the two chambers 10 and 11 of different diameters. An aperture 12 is provided in the outer 25 face of the raised hub 9 which extends from the center of the hub 9 in a slot design to one edge of the circumference thereof.

A circular spring 13 having one end turned inwardly toward the central area thereof, and the second end bent angularly inwardly toward the central area thereof to be bent again upwardly to form a V-shaped end 13a thereon within the area of the circle formed by the spring 13. The spring 13 is adapted to be slightly compressed 30 so as to be easily positioned within the slot 11, its resiliency maintaining it in such a position so that the V-shaped end 13a thereof extends across the slotted aperture 12 thereby restricting said slot.

40 A button 14 having a shaft 15 carried by the center thereof and a shaft head 16 affixed thereto is adapted to be moved into the slot 12 with the head 16 positioned in the aperture 10 and the shaft 15 in the apertured slot 12, the button itself 45 extending outward and beyond the face of hub 9.

When the button is slidably moved into engagement with the hub 9 the V-shaped end 13a of the spring 13 offers a tensional resistance to the shaft 15 of the button, but when force is applied 50 the shaft 15 compresses the spring 13 sufficiently to allow the shaft to pass the apex of the V end 13a bringing it in a position in the center of hub 9. When the shaft 15 has been forced past the V-shaped end of the spring 13 the resiliency 55 of the spring causes the end 13a to return to its

restrictive position in the slotted aperture 12 preventing the button from sliding out of the button holder without the exertion of force thereon.

If the button holder B is affixed to the garment 4 so that the open end of the slotted aperture 12 is away from the opening of the garment which is to be buttoned closed the stress on the button will be against the solid side of the hub 9 and thereby eliminate the possibility of the button being forced past the V spring 13a.

It can thus be seen that the provision of a plurality of such button holders upon a garment in those positions where buttons are desired that the buttons can be easily removed from the garment to prevent their being broken during the cleaning or washing of the garment, and that an attractive garment may be perfected when buttons are changed on the garment to match the jewelry or accessories to be worn with the garment.

In Figure 8, the member B' is provided with an ear 28 which is bent around the straight part 21 of the spring 13' to restrain the latter from accidental shifting.

Having thus described and explained this invention that I desire to claim in Letters Patent is:

A device for detachably securing a button to fabric, the fabric having an opening at the point where the button is to be attached, said device comprising a thin flat plate arranged upon the inner face of the fabric adjacent to the opening including pointed elements carried by one side thereof which pierce the fabric, the pointed elements being bent over upon the outer face of the fabric to secure the plate to the same, a central upstanding outwardly extending boss secured to the plate and projecting through the opening of the fabric and beyond the outer face of the fabric, the boss having a recess formed in its outer end and extending through its side at one

point, an outer thin substantially flat companion plate mounted upon the outer face of the fabric adjacent to the first-named plate and having its marginal edge formed for interlocking engagement with the bent over pointed elements for securing the outer companion plate to the fabric, a central upstanding tubular hub secured to the outer companion plate and projecting outwardly thereof, the tubular hub having a substantially flat outer end provided with a slot which extends through the side of the hub at one point, the hub having a central bore extending through the outer companion plate and receiving therein the upstanding boss of the first-named plate, the outer end of the boss within the bore being spaced inwardly from the outer end of the hub, the bore of the hub between the outer ends of hub and boss being enlarged for forming a chamber which is substantially wider than the slot in the outer end of the hub, the side of the tubular hub having an opening the outer portion of which leads into the slot in the outer end of hub, the inner portion of the opening in the side of the hub being enlarged and having substantially the same width as the recess of the boss and being arranged in communication with such recess, and a yielding element mounted within the chamber between the outer ends of the hub and boss and having a yielding retainer part projecting across the slot in the outer end of the hub.

GORDON O. BOWIE.
